UNITED STATES PATENT OFFICE.

JOHN M. WILLIAMS, OF HAZLETON, PENNSYLVANIA.

COMBINED TABLET, PAPER-WEIGHT, AND BLOTTER.

SPECIFICATION forming part of Letters Patent No. 360,750, dated April 5, 1887.

Application filed December 10, 1886. Serial No. 221,194. (No model.)

To all whom it may concern:

Be it known that I, JOHN M. WILLIAMS, of Hazleton, in the county of Luzerne and State of Pennsylvania, have invented a new and 5 Improved Combined Tablet, Paper-Weight, and Blotter, of which the following is a specification, reference being had to the annexed drawings, forming a part thereof, in which—

Figure 1 is a plan view, and Fig. 2 is a side 10 elevation.

Similar letters of reference indicate corresponding parts in both views.

The object of my invention is to provide for the use of book-keepers and others a tablet 15 carrying upon its under surface one or more sheets of blotting-paper, and having upon its upper side a writing-surface provided with cavities for receiving wet and dry sponges, pins, &c., and furnished upon one edge with 20 hooks for holding a pencil.

The block A, forming the body of the tablet, is preferably made of a piece of slate having an inclined surface, a, which is smoothed and prepared for writing. In the thicker end 25 of the tablet are formed three cavities, b c d. In the cavity b is placed a roll of pins, e, and in the cavities c d are placed sponges f g, the sponge f being dry and the sponge g being kept moist. Hooks i project from the side of 30 the tablet A, for supporting a pencil, i. The sponge g is designed for moistening the fingers for handling bills and papers, and the

sponge f is designed to be used for erasing marks from the surface of the tablet, the said sponge being moistened by application to the 35 sponge g. One or more sheets of blotting-paper, j, are secured to the under surface of the tablet A.

My improved tablet is designed to be used upon desks in the counting-room for the purpose of making temporary memoranda and for supporting a sponge and a quantity of pins 40 in convenient position for use.

Having thus fully described my invention, I claim as new and desire to secure by Letters 45 Patent—

1. In a combined tablet, paper-weight, and blotter, the combination, with the tablet A, provided with an inclined surface, a, and cavities b c d, of the blotters j, substantially as 50 shown and described.

2. As an improved article of manufacture, a combined tablet, paper-weight, and blotter formed of a block of slate having an inclined surface, a, and provided with cavities b c d, 55 the pin-roll e, sponges f g, placed in the said cavities, the hooks h, projecting from one edge of the tablet, and the pencil i, received in the hooks, substantially as shown and described.

JOHN M. WILLIAMS.
